(57) **CLAIM**

The ornamental design for a guitar-shaped hair clip, as shown and described.

DESCRIPTION

FIG. 1 is front perspective view of a guitar-shaped hair clip showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top elevation view thereof;

FIG. 7 is a bottom elevation view thereof; and,

FIG. 8 is a front perspective view thereof showing the guitar-shaped hair clip of the present invention in use.

The portions of the figures illustrated in broken lines are provided for illustrative purposes only and form no part of the claimed design.
